(57) **CLAIM**

The ornamental design for a power base for electric kettle, as shown and described.

DESCRIPTION

FIG. 1 is a front, left and top perspective view of a power base for electric kettle showing our new design;

FIG. 2 is a front, right and top perspective view thereof;

FIG. 3 is a rear, left and bottom perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof;

FIG. 9 is a left side elevational view thereof; and,

FIG. 10 is a front, right and top perspective view of the power base for electric kettle in accordance with our new design illustrating a state in which environmental structures (batteries and an electric kettle) are attached to the power base for electric kettle.

The broken lines on the power base for electric kettle depict portions of the power base that form no part of the claimed design. In FIG. 10, the broken lines showing a kettle and batteries depict environmental subject matter only, and form no part of the claimed design.

1 Claim, 10 Drawing Sheets
